UNITED STATES PATENT OFFICE.

ARTHUR V. A. McHARG, OF NEW YORK, N. Y., ASSIGNOR TO THOMAS E. MURRAY, OF NEW YORK, N. Y.

SEAL-FASTENING.

1,054,436.

Specification of Letters Patent. Patented Feb. 25, 1913.

Application filed August 14, 1912. Serial No. 714,966.

To all whom it may concern:

Be it known that I, ARTHUR V. A. McHARG, a citizen of the United States, residing at New York, in the county of New York and State of New York, have invented 5 a certain new and useful Improvement in Seal-Fastenings, of which the following is a specification.

The invention relates to seal fastenings, 10 and consists in the construction, hereinafter set forth, whereby access to the ends of the shackle, secured within the casing cannot be had without breaking a button of fictile material closing said casing and locked therein.

15 In the accompanying drawings—Figure 1 is a perspective view of my seal fastening. Fig. 2 shows the case in section and the position of the parts while the breakable button is being inserted. Figs. 3 and 4 are 20 similar views, showing the button in locked position, the locking spring in Fig. 3 being in elevation, to exhibit the slit therein. In Fig. 4 said spring is shown in section. Fig. 5 is a top view of the casing, without 25 the breakable button.

Similar letters of reference indicate like parts.

The casing A is box-shaped, preferably cylindrical and of metal, the rim being bent 30 inward to form the flange B. In the bottom of the casing are holes to receive the ends of the shackle wire C, which ends, after insertion, are twisted together, as shown at D.

35 E is a breakable button, preferably of porcelain or other fictile material, made with a head F and a circumferential groove in its body portion to receive the locking spring G. Said spring has an inclined slit H in it, and its outer periphery is beveled 40 downwardly. The area of the body portion of the button is of such size as to allow

said body portion to enter the opening in the case surrounded by flange B.

In operating the device, the shackle wire 45 is first put in the holes in the bottom of the case and its ends are twisted together, as described. The button is then inserted in the opening, the spring G being compressed so as to close the slit H, as shown in Fig. 2. 50 The button is pressed inwardly until the spring passes below the flange B, when the spring then expands, as shown in Figs. 3 and 4. The button cannot afterward be withdrawn because the expanded spring 55 locks against the under side of flange B. The head F covers the joint between the flange and the button, and prevents the introduction of any tool to tamper with the spring. 60

I claim:

1. A cup-shaped casing, having an inwardly flanged rim, a headed plug having its shank fitting in said rim opening, a locking device on said shank engaging with said rim, and a shackle loop entering and secured in said casing between said plug and the bottom of said casing. 65

2. A seal fastening, comprising a cup-shaped casing, having an inwardly flanged 70 rim, a plug having a circumferential groove and received in said casing, a spring seated in said groove and compressible to permit the insertion of said plug, and after insertion expanding to engage said rim, and a 75 shackle loop entering and secured in the space in said casing between said plug and the bottom of said casing.

In testimony whereof I have affixed my signature in presence of two witnesses.

ARTHUR V. A. McHARG.
